UNITED STATES PATENT OFFICE.

WALTER S. BRIDGES, OF CHICAGO, ILLINOIS.

HINGE.

1,135,349.

Specification of Letters Patent. Patented Apr. 13, 1915.

Application filed May 4, 1914. Serial No. 836,243.

To all whom it may concern:

Be it known that I, WALTER S. BRIDGES, a citizen of the United States, residing at Chicago, in the county of Cook and State 5 of Illinois, have invented certain new and useful Improvements in Hinges, of which the following is a specification.

This invention relates to double swinging hinges for doors, and its object is to 10 provide a strong and durable hinge of novel design which allows the door to swing freely and which provides a secure support for the door. This object is attained by means of a combination and arrangement of parts 15 to be hereinafter described and claimed, reference being had to the accompanying drawing, in which—

Figure 1 is an elevation of a fragment of a door equipped with my improved hinge; 20 Fig. 2 is a horizontal section on the line 2—2 of Fig. 1; Fig. 3 is a section on the line 3—3 of Fig. 2; Fig. 4 is a view similar to Fig. 2 showing a modification, and Fig. 5 is a section on the line 5—5 of Fig. 4.

25 Referring specifically to the drawing, 5 denotes the door and 6 the jamb of the frame to which the door is hinged. In the edge of the jamb which faces the hinge edge of the door is a recess in which is set a heavy 30 flat metal plate 7 which projects from the jamb to enter a recess 8 in the hinge edge of the door, the projecting end of the plate being loose in the edge recess of the door so that the latter may swing freely. The edge 35 of the door is reinforced by a metal strip 9 above and below the recess 8. In the top of the projecting end of the plate 7 is a V-shaped groove or channel, the branches 10 of which are curved and extend divergently 40 from the angle in the direction of the door. The curve is substantially quadrantal. From the upper wall of the recess 8 in the door depends a pivot 11 which extends into the grooves 10. The pivot 11 is midway be- 45 tween the sides of the door 5, and the angle or meeting point of the grooves 10 coincides therewith. Thus, when the door is closed, the pivot is located at the junction of the grooves. When the door is swung 50 open to the dotted position shown in Fig. 2, the pivot travels along that groove which points toward the side to which the door is swung. The pivot travels along the other groove when the door is swung to the oppo-

site side. The grooves 10 slope downward 55 toward the angle, which allows the door 5 to return by gravity automatically to closed position. The height of the recess 8 is such as to allow the door to rise slightly when it swings open, and to drop down when it 60 closes. The pivot 11 carries a roller 12 which travels on the floor of the grooves. The periphery of the roller is rounded to prevent binding at the junction of the 65 grooves.

The drawing shows only one of the hinge members, but it is to be understood that the door will be equipped with two or more of such members.

At the outer ends of the grooves 10 the 70 inner walls thereof have notches 13 which will act as stops when the door is intended to stay wide open for any length of time, by the pivot 11 entering said notches.

Referring to Figs. 4 and 5, a plate 14 75 corresponding to the plate 7 is provided, said plate 14 having slots 15 arranged in the same manner as the grooves 10. The door 5 has a pivot pin 16 extending into said slots, and working in the same manner as the pivot pin of the first described structure. The pin 16 has a shoulder 17 engaging the top of the plate 14 adjacent to the slots. To permit the door to close automatically, the plate 14 has an upward 80 slant from the jamb 6 toward the door 5.

I claim:

1. The combination with a jamb and a door, the door having a recess in its hinge edge, a plate fixed to the jamb and projecting therefrom into the edge recess of the door, the face of the projecting end of the plate having grooves which are connected at their inner ends and extend divergently therefrom, said grooves sloping downward 90 toward their meeting ends, and a pivot carried by the door in the edge recess thereof and extending normally into the meeting ends of the grooves, and movable therefrom into either one of said grooves when the 95 door is swung.

2. The combination with a jamb and a door, the door having a recess in its hinge edge, a plate fixed to the jamb and projecting therefrom into the edge recess of the door, said plate having recesses which are connected at their inner ends and extend 100 divergently therefrom, and said member

also having inclined surfaces following the direction of the recesses, and a pivot carried by the door in the edge recess thereof, and extending normally into the meeting 5 ends of the recesses, said pivot having means engageable with the aforesaid inclined surfaces.

In testimony whereof I affix my signature in presence of two witnesses.

WALTER S. BRIDGES.
